Design for a Carpet Pattern

The Schedule referred to in these Letters Patent and making part of the same.

To all whom it may concern:

Be it known that I, Elinor J. May, of Lowell in the County of Middlesex, State of Massachusetts have originated and designed a new pattern for carpets or other fabrics, of which the following is a full, clear and exact description, reference being had to the accompanying drawings making part of this specification:

A, is a quarter of a cross resting on Figure B, — Figure B, is surrounded by branches C, D, D, is a bar when matched will form a diamond. The rest of the design consists of flowers, leaves and Spring-work overlapping bar D, D,

The colors employed for the different portions of the design may be varied to suit the taste and wish of the manufacturer.

Claim.

What I claim as my invention and desire to secure by Letters Patent is, The Design or Pattern for Carpets or other Fabrics, herein set forth.
